a corporation of Delaware

Application March 29, 1943, Serial No. 480,978

10 Claims. (Cl. 178—7.5)

1

This invention relates to amplifiers and particularly to amplitude discriminating amplifiers for expanding non-linearly one of the components of a composite television signal.

According to conventional television practice, a carrier wave is modulated by both video and synchronizing components to form a composite television signal. At the receiver, it frequently is necessary to amplify non-linearly one of the components and sometimes to simultaneously suppress the other component. When the video component is so amplified, it is possible to effect a gamma control such that the relative contrast between some parts of the reproduced picture differs from the relative contrasts between other parts of the picture. For example, it may be desirable to deemphasize the contrast between the darker parts of the picture while at the same time to emphasize or accentuate the contrast between the lighter parts of the picture. The gamma control may be accompanied by a separation of the video signal component from the synchronizing component of the composite television signal.

For the synchronous operation of the receiving apparatus, it also is necessary to separate the synchronizing and video components in such a manner that the synchronizing component is retained and the video component is suppressed. The separation of the two components of the television signal may be accomplished by means of limiter tubes. Such tubes may be utilized to separate the two signal components and to suppress any desired one of the components.

Numerous circuits have been devised for operating limiter tubes. One expedient is to bias the tube for saturation at a predetermined signal level. The composite television signals are applied to the input circuit of the tube so that one of the signal components drives the tube to saturation while the other signal component is amplified in the output circuit. A disadvantage of this type of limiter is that it can be used only in cases where the direct current signal level of the picture to be reproduced has been established.

Another type of limiter employs a tube which is biased to effect plate current cut-off. The composite television signals are impressed upon the input circuit of the tube in such a manner that one of the signal components drives the potential of the grid of the tube beyond the point of plate current cut-off and the other signal component is amplified in the output circuit of the tube. This type of limiter can be arranged so that the

2

grid adjusts itself to a direct current signal level such that the maximum positive peaks of one of the signal components produce a zero bias of the grid.

5 Limiters of these two types and others employed heretofore effect the desired signal separation and reproduce in amplified form, without substantial distortion, the signal component which is retained.

10 As is well understood in the art, however, a disadvantage of this latter type of limiter is that it requires television signals of considerable amplitude in order that the signal component which is to be suppressed have a voltage which will effect the cut-off of plate current in the tube at the desired point of the signal wave. For example, where it is desired to recover the synchronizing component to the exclusion of video component from a composite television signal 15 constituted in accordance with the present standards adopted by Radio Manufacturers Association in the United States, the grid voltage to effect plate current cut-off should correspond to the television signals representing the black portions of the picture. Wherever possible it is desirable to separate the video signal component from the synchronizing signal component in the signal wave derived from the detector of the receiver. Hence, for the operation of a limiter of the grid cut-off type, it is necessary to provide one or more amplifiers for the demodulated signals in order to obtain the required amplitude in the case of weak signals. Also, where it is desired to recover the video component to the exclusion of the synchronizing component and to amplify non-linearly the video component for the purpose of gamma control, it is desirable to accomplish this result before the video component is amplified.

20 15 An object of the present invention, therefore, is to provide, in a television system, an improved signal separator, the operation of which is independent of the signal strength or the direct current signal level.

25 20 Another object of the invention is to provide an amplifier for obtaining non-linear distortion of a portion of a composite television signal, whereby the distorted portion may be separated from other portions of the television signal.

30 25 Still another object of the invention is to provide, in a television receiver, an improved signal limiter wherein there is employed a regenerative voltage feed-back from the output circuit of a triode to the input circuit thereof, whereby to

separate the synchronizing and video components of weak as well as strong composite television signals.

A further object of the invention is to provide an improved non-linear feed-back amplifier which is discriminatory of signal amplitude, whereby only the synchronizing component of a composite television signal is amplified.

A still further object of the invention is to provide a non-linearly distorting amplifier, whereby the video component of a composite television signal may be recovered in such form to effect a gamma control of a reproduced picture.

In accordance with the present invention, there is provided a space discharge device such as a three element vacuum tube which employs a self-biasing grid circuit. The cathode circuit of the tube is made degenerative and there is coupled to the cathode a direct current regenerative feed-back circuit. The arrangement is such that the regenerative component is large relative to the degenerative component so as to effect a discrimination in signal amplitude, whereby all signals of less than a predetermined positive amplitude are suppressed in the output circuit. Also the signals which are reproduced in the output circuit are amplified in a non-linear manner with respect to the corresponding signals impressed upon the input circuit. The magnitude of the distortion varies directly as a function of the impressed signal amplitude.

Whether the reproduced signals correspond to the video or synchronizing components depends upon the polarity of the composite television signal as it is impressed upon the input circuit of the amplifier.

For a better understanding of the invention, together with other and further objects thereof, reference is had to the following description taken in connection with the accompanying drawings, and its scope will be pointed out in the appended claims.

In the accompanying drawings:

Fig. 1 is a circuit diagram of a television receiver, partially schematic, embodying the present invention, as employed to recover the synchronizing component from a composite television signal;

Fig. 2 is a graphic representation of typical television signals in relation to the plate current versus grid voltage characteristic of a vacuum tube;

Fig. 3 illustrates typical television signal voltages appearing in the circuits of Fig. 1 which are of assistance in explaining the operation of the illustrative embodiment of the invention; and

Fig. 4 is a circuit diagram of a television receiver, partially schematic, embodying the present invention as employed to recover the video component from a composite television signal in a form suitable for effecting a gamma control of the reproduced picture.

Referring now more particularly to Fig. 1 of the drawings, there is shown schematically a superheterodyne receiver embodying the present invention in a preferred form. The television signals which are intercepted by an antenna 10 are converted into an intermediate frequency and demodulated by conventional radiant energy receiving apparatus 11, labeled in the drawings as "Frequency converter, I. F. amplifier, detector." The rectified television signals consisting of the video signals and the synchronizing impulses are amplified by a video amplifier 12. The amplified video signals are impressed upon the grid

of a cathode ray tube 13 for controlling, in a conventional manner, the shading of the picture to be reproduced.

The demodulated video and synchronizing signals are coupled by means of a condenser 14 to the input circuit of a space discharge device, such as a triode vacuum tube 15. The input circuit includes the cathode and the control grid of the tube which are interconnected by resistance means. This means comprises a series arrangement of a grid leak resistor 16 and a cathode follower resistor 17, and the junction point of these resistors is grounded. The condenser is connected to the grid leak resistor portion of the input circuit resistance element. There also is provided a variable resistor 18 connected between the anode of the tube and the cathode follower resistor 17. A battery 19 is connected through a resistor 20 to the anode of the tube.

It will appear from subsequent portions of the description that there is developed at the cathode of the tube 15 a square-topped impulsive voltage at the synchronizing signal frequency. This voltage is applied to conventional synchronizing and scanning control apparatus 21, the purpose of which is to separate the horizontal and vertical synchronizing signals so as to control the scanning generators. The horizontal and vertical generators are connected to the respective sets of deflector elements 22 and 23, whereby the usual deflections of the electron beam may be effected.

The signal which appears in the output circuit of detector 11 has a form such as that illustrated by the curve 24 of Fig. 3. This signal consists of video and synchronizing components and varies in polarity so that the negative portions thereof constitute some of the video signals and the positive portions thereof constitute the remainder of the video signals and the synchronizing impulses. If such a signal were applied to a prior art limiter, having a tube biased to effect plate current cut-off, the signal would have the relation of the curve 25 of Fig. 2, with respect to the plate current versus grid voltage characteristic of the tube 15.

This would be the case in the present amplifier if it were not for the regenerative feed-back voltage provided. It is seen that the tube has a zero grid-to-cathode bias corresponding to the maximum positive peaks of the signal. If the signal applied to the input circuit of the tube is relatively weak, the amplitude is insufficient to carry the grid sufficiently negative to effect cut-off of the plate current below the bases of the pedestals of the synchronizing impulses. The result produced in such a case is illustrated in Fig. 2 in which the curve 26 represents the plate current derived from a weak signal applied to a signal limiter of the grid cut-off type. Thus, separation of the video and synchronizing signals by such a device is impossible, unless the signal strength is increased by amplification before the signal is applied to the limiter.

The apparatus in accordance with the present invention combines the amplifying and limiting operations in the circuits associated with a single three-element tube. Assume for the moment that, when a composite television signal having the form of the curve 24 of Fig. 3 is applied to the input circuit of the tube 15, the feed-back circuit is inoperative. The anode voltage of the tube then would fluctuate as illustrated by the curve 27 and the cathode voltage as shown by

the curve 28. The ranges of variation of the anode and cathode voltages are substantially different by reason of the constants selected for the resistors 17 and 20. Satisfactory operation using the tube of the 6J5 type has been secured with the resistor 17 having a value of a few thousand ohms and the resistor 20 having a value of approximately twenty-five times the value of the resistor 17. When using circuit elements having these constants, the battery 19 has a potential of 300 volts.

The amplitude of the positive potential of the cathode increases as the amplitude of the signal increases in a positive direction. The amplitude of the positive anode potential decreases as the amplitude of the signal increases in a positive direction. As would be expected, the voltage developed in the cathode follower resistor 17 has a degenerative effect upon the input circuit of the tube 15.

Actually, however, a portion of the anode voltage is applied to the cathode of the tube by means of a direct current coupling comprising the variable resistor 18. This feed-back voltage has a regenerative effect upon the input circuit of the tube and, by means of a suitable adjustment of the resistor 18, the regenerative component is made large relative to the degenerative component.

The result produced by the regenerative feed-back voltage is an amplitude distortion or expansion of the signal applied to the input circuit of the tube 15. Also, by reason of the described combination of regenerative and degenerative components which have materially different ranges of variation, there is produced a net feed-back voltage to the input circuit which is non-linear with respect to the signal voltage. The effect of the feed-back voltage is much greater in the region of the positive signals than it is in the region of the negative signals. Consequently, the positive portions of the signals are expanded more than the negative portions.

Also, by reason of the direct current coupling between the output and input circuits of the tube, a portion of the positive potential of the battery 19 appears as a steady direct current voltage at the cathode. The effect of this arrangement is to shift the average bias of the tube further toward the point of plate current cut-off.

Thus, when a signal such as that represented by the curve 25 of Fig. 2 is impressed upon the resistor 16 of Fig. 1, the resultant expanded signal applied to the input circuit of the tube by the apparatus in accordance with this invention is represented by the curve 29 of Fig. 2. It is seen that the synchronizing signal portions have been amplified considerably more than the video signal portions. Also, it is seen that the bases of the pedestals of the synchronizing impulses coincide approximately with the point of plate current cut-off. Such signals produce plate current in the tube 15, having the form illustrated by the curve 30. Thus, the video signals are suppressed completely in the output circuit.

The voltage fluctuations actually occurring at the anode of the tube 15 are represented by the curves 31 of Fig. 3. Similarly, the actual voltage fluctuations occurring at the cathode of the tube are illustrated by the curves 32. Either or both of these two voltages may be utilized for synchronizing purposes. However, it is preferable to use the voltage derived from the cathode for the reason that it does not vary in its maximum amplitude appreciably with variations of the sig-

nal strength. The anode voltage has a greater maximum amplitude variation under these conditions.

It is evident that, if the composite television signal is applied to the input circuit of the tube 15 in reverse polarity to that described, the video signal component will be positive and the synchronizing signal component will be negative. By the action of the amplifier the positive video signals will be amplified in the output circuit of the tube distorted in amplitude and the negative synchronizing signals will be suppressed. Also, since the magnitude of the distortion of the amplified video signals depends upon the amplitude of these signals, the signals representing the darker portions of the picture are distorted less than the signals representing the lighter portions of the picture. Consequently, it is seen that the amplifier embodying the present invention is also susceptible of operation, whereby to effect a gamma control of the reproduced picture.

Such a use for the amplifier embodying the instant invention is illustrated in Fig. 4. Circuit elements corresponding to similar elements of Fig. 1 are given identical reference characters in the two figures. The demodulated composite television signals are impressed upon the input circuit of the tube 15 in such a manner that the video signals are of positive polarity and the synchronizing signals are of negative polarity. The output circuit including the resistor 17 is connected to the input circuit of the video amplifier 12. Also the demodulated signals are impressed upon a synchronizing and video signal separator 33 which may be of the type illustrated in Fig. 1, if desired.

The operation of the distortion amplifier as a device for effecting a gamma control of the reproduced picture is believed to be obvious in view of the detailed description of its operation as a limiter. By reason of the described polarity of the composite television signal as applied to the input circuit of the amplifier tube 15 of Fig. 3, the video component appears in the output circuit in a non-linearly distorted form. Such a signal, when applied to the grid of the cathode ray tube 13, controls the reproduction of the picture in a manner to vary the contrast in the light and dark portions of the picture.

While there has been described what at present is considered the preferred embodiment of the invention, it will be obvious to those skilled in the art that various changes and modifications may be made therein without departing from the invention and, therefore, it is aimed in the appended claims to cover all such changes and modifications as fall within the true spirit and scope of the invention.

What is claimed is:

1. Apparatus for effecting a non-linear amplification of a composite television signal including video and synchronizing components comprising a single vacuum tube having input and output circuits, means for impressing said composite television signal upon said input circuit, a regenerative feed-back connection between said output and input circuits to effect a non-linear amplitude distortion of said amplified signal, and means including said feed-back connection to reproduce in said output circuit only one of said composite television signal components.

2. In a television receiver, means for receiving a composite television signal including video and synchronizing components, an amplifier tube having input and output circuits, means for im-

pressing said received television signal upon the input circuit of said amplifier tube in such a manner that said video component is positive and said synchronizing component is negative, means for regeneratively coupling said input and output circuits to produce in the output circuit of said amplifier tube non-linearly distorted video signals, and means including said coupling to effect a gamma control of a picture reproduced from said video signals.

3. Apparatus for separating the video and synchronizing components of a composite television signal comprising a vacuum tube having an anode, a cathode and a control grid, an input circuit including said cathode and said grid, an output circuit including said cathode and said anode, means comprising a direct current coupling including a resistor between said anode and said cathode to effect a non-linear regenerative feed-back from said output circuit to said input circuit, and means including said coupling to reproduce said synchronizing component in said output circuit to the exclusion of said video component.

4. Apparatus for separating the video and synchronizing components of a composite television signal comprising, a vacuum tube having an anode, a cathode and a control grid, an input circuit including said cathode and said grid, an output circuit including said cathode and said anode, means comprising a direct current coupling between said anode and said cathode to effect a regenerative feed-back from said output circuit to said input circuit, and means including said coupling to reproduce said synchronizing component in said output circuit to the exclusion of said video component.

5. Apparatus for separating the video and synchronizing components of a composite television signal comprising a vacuum tube having an anode, a cathode and a control grid, an input circuit including said cathode and said grid, an output circuit including said cathode and said anode, a resistor connected to said cathode in series with said input and output circuits, a direct current coupling including a resistor between said anode and said cathode, and means including said coupling to reproduce said synchronizing component in said output circuit to the exclusion of said video component.

6. Apparatus for separating the video and synchronizing components of a composite television signal comprising a vacuum tube having an anode, a cathode and a control grid, an input circuit including said cathode and said grid, an output circuit including said cathode and said anode, self-biasing means in said input circuit including a condenser in series with said input circuit and a leak resistor in shunt with said input circuit, a resistor connected to said cathode in series with said input and output circuits, a direct current coupling including a resistor between said anode and said cathode, and means

including said coupling to reproduce said synchronizing component in said output circuit to the exclusion of said video component.

7. An amplifier for alternating current signals comprising a vacuum tube having an anode, a cathode and a control grid, a resistance element connected between said grid and said cathode, means for impressing said signals upon a portion of said resistance element, and means including a resistor for impressing upon another portion of said resistance element a potential derived from said anode, whereby to increase the potential of said grid with respect to said cathode sufficiently to suppress in said output circuit signals of less than a predetermined positive amplitude.

10 8. An amplifier for alternating current signals comprising a vacuum tube having an anode, a cathode and a control grid, a series connection of a grid leak resistor and a cathode follower resistor, means for impressing said signals upon said grid leak resistor, and means including a variable resistor for impressing upon said cathode follower resistor a potential derived from said anode to increase the potential of said grid with respect to said cathode, said anode-derived potential having a magnitude determined by said variable resistor whereby to suppress in said output circuit signals of less than a predetermined positive amplitude.

15 9. A combined signal limiter and amplifier for separating the synchronizing component from a composite television signal including video and synchronizing components comprising a single space discharge device having input and output circuits, means responsive to signals having greater than predetermined amplitudes for automatically biasing said input circuit to effect output current cut-off of negative portions of said signals, means coupling said output and input circuits responsive to signals having lesser than said predetermined amplitudes for regenerating said last named signals, and means including said coupling means, to effect said output current cut-off of the video component of said last-named signals.

20 10. A combined signal limiter and amplifier for separating the synchronizing component from a composite television signal including video and synchronizing components comprising a vacuum tube having input and output circuits, means including a condenser in series with said input circuit and a resistor in shunt with said input circuit and responsive to large amplitude signals for automatically biasing said input circuit to effect output current cut-off of negative portions of said signals, means including a resistor coupling said output and said input circuits for regenerating small amplitude signals, and means including said coupling to effect said output current cut-off of the video component of said small amplitude signals.

MADISON CAWEIN.
